**VOLTAGE REGULATION TAP SELECTOR SWITCH
WITH RADIAL CONTACT MEANS**

René Pensis, Jumet, Belgium, assignor to Ateliers de Constructions Électriques de Charleroi (ACEC), Brussels, Belgium

Filed Mar. 23, 1961, Ser. No. 133,536

1 Claim. (Cl. 200—11)

The tap selectors for switches used in the voltage regulation of loaded transformers usually comprise cylindrical casings formed of insulating rods disposed peripherally and vertically in relation to the wall of the main tank of the transformer. Fixed contacts connected to the taps of the transformer windings are secured on the rods. In the case of 3-phase switches, the three phases are located one above the other. This arrangement is considered conventional when applied to so-called concentric-winding transformers.

In said concentric windings, the regulating taps are generally made on the outside windings in order that the connection cabling lie at the same level between the taps proper and the corresponding contacts of the selectors. This arrangement facilitates the making of these connections particularly in high tension installations because such straight-line positioning of the connections entails greater homogeneity in the insulation of the conductors.

It is a different matter if a selector as described above is to be applied to transformers of the shell-core type. In such cases, the regulating taps provided on the windings are located on the upper portion thereof.

To reach the fixed contact of the selectors, the connection must travel a long and sinuous path and this arrangement is detrimental to the good insulation of the conductors and further requires great precautions in making the connections.

One object of the invention is to provide a selector which, when used with shell-core transformers, eliminates the above noted objections.

The invention is characterized in that the contacts, which are joined to the regulating taps, are distributed in two groups located at each end of an insulating cylinder and are equally spaced in each group. The effective surfaces of the contacts are located outside the cylinder and their connecting lugs to the conductors, joined to the regulating contacts, are located inside the said cylinder.

The invention is also characterized in the fact that the insulating cylinder lies horizontally, that is, normal to the lateral wall of the transformer tank.

Other features of the invention will appear as the following description proceeds, having reference to the annexed drawings which pertain to a non-limitative embodiment.

FIG. 1 is a diagram of the regulation of one phase of a loaded transformer.

FIG. 2 illustrates a diagrammatic arrangement of a selector according to the invention.

FIGS. 3 and 4 pertain to one embodiment of a selector according to the invention.

FIG. 5 is a partial perspective view of the selector of the invention.

2

In transformers, with regulation when on load, the switching from one tap to the next is made without interrupting the load, owing to a switch which momentarily shunts the contact taps.

5 This regulating switch must permit:

(1) The selection or choice of the regulating winding tap.

(2) The switching proper, that is, the passing from one tap to another without interrupting the load.

10 These two operations are usually carried out by two different elements: a selector and a breaker.

The diagram of FIG. 1 shows a simple case of the phase regulation of a transformer when a selecting switch 1 is in position 2.

15 As is known, the choice of a tap is made on the selector S by the cascade displacement of brushes B₁ and B₂. In order to travel the thirteen regulating positions provided in the present case, brush B₁ successively pass on the fixed contacts of the odd-numbered series c, e, g, i, k, m and o by joining them successively with a common point S₁ whereas brush B₂ pass successively on the fixed contacts of the even-numbered series d, f, h, j, l and n by joining them successively to a common point S₂. These common points S₁ and S₂ are joined to breaker R.20 In such breaker R, a movable support member ms carries a plurality of contacts coupled to one terminal of the windings while a fixed support member fs carries a corresponding plurality of contacts divided into two groups which are coupled via adequate impedances ip respectively to two successive taps of the windings by means of S₁ and S₂. The moving support member is moved with respect to the stationary support member and pairs of contacts are sequentially connected so that the tap may be changed without any interruption of current flow in the load, the fraction of the winding between the taps being shunted by the impedances ip during the passage from one tap to another, for example from tap d to tap e after displacement of brush B₁ from tap d to tap e. The brush B₂ is then displaced to the tap f and the same operation is continued until the required voltage is reached.25 In the case of a three-phase transformer, the selector comprises three devices similar to those described above. The brushes B₁ of the three devices move simultaneously and the same is true of the three brushes B₂.

30 Generally, the selector is formed of two end flanges made of light alloy and joined together by means of insulating tubes which form a casing; the said casing supporting the fixed contacts which are distributed in horizontal planes, positioned one above the other.

35 The fixed contacts of each phase are distributed in two superposed horizontal planes; one plane for the odd-numbered contacts and one plane for the even-numbered contacts. The selector thus has six layers of superposed contacts, three layers for the odd-numbered contacts and three layers for the even-numbered contacts. The odd-numbered contacts and the even-numbered contacts of each phase are respectively brought in contact to one common point S₁ and to one common point S₂ by means of one brush B₁ and one brush B₂. The common points S₁ and S₂ are formed as rings (there being one ring per layer) and joined to breaker R.

Brushes B_1 and B_2 as well as rings S_1 and S_2 are located inside the selector, whereas, the tap connections to the fixed contacts lie outside thereof.

If such a selector is used with a transformer of the shell-core type, wherein the regulating taps are located at the upper portion of the windings, the connector joining the taps to the selector will contain several bends which are detrimental to their good insulation.

The odd-numbered fixed tap contacts, that is, contacts c, e, g, i, k, m, n, o of the three phases are evenly distributed on one of the extreme faces of insulating cylinder 5; all of said odd-numbered contacts of each phase taking up one-third of the periphery of the insulating cylinder 5. The effective surface of the contacts face outwardly of the cylinder whereas their connection lugs 13 to the winding taps (FIGS. 3 and 5) face inwardly of the same cylinder.

Three brushes B_{1A}, B_{1B}, B_{1C} are spread apart 120° and are secured onto an insulating movable ring 6 exteriorly concentric to cylinder 5 which carries, on a 240° segment, a toothed portion forming rack 7. A toothed pinion 8 meshes with rack 7 allowing, by its rotation, the movement of brushes B_1 and the placing in contact of each of the fixed contacts of one phase with common points obtained by means of segments S_{1A}, S_{1B}, S_{1C} , respectively corresponding to the three phases.

The even-numbered fixed tap contacts, that is, contacts b, d, f, h, j, l and n , are distributed on the other end of cylinder 5. Three brushes B_{2A}, B_{2B}, B_{2C} are also disposed 120° apart and secured onto a movable ring 10 exteriorly concentric to cylinder 5 and also having a toothed portion 12. It is possible by means of the three brushes to bring together each of the fixed contacts of one phase with one of the three segments S_{2A}, S_{2B}, S_{2C} respectively corresponding to the three phases by the rotation of toothed pinion 11.

The three segments S_{1A}, S_{1B}, S_{1C} and the three segments S_{2A}, S_{2B}, S_{2C} are connected to the contacts of the three fixed support members fs of the breaker R as described in the simple case of the phase regulation.

(FIG. 2).

Toothed pinions 8 and 11 are actuated step-by-step, in

one direction or the other, by means of a known mechanism of the Maltese cross type, as shown in FIG. 7.

For instance, this mechanism drives pinion 8 in the first place; this pinion which meshes with rack 7 produces the rotation of movable ring 6 at such an angle that the brushes B_{1A}, B_{1B}, B_{1C} jump, for instance, from contacts c to contacts e . This operation is followed by tugging of breaker R which carries the load from segments S_2 to segments S_1 . In the next operation, the Maltese cross mechanism drives pinion 11 which due to its meshing with rack 12 will pivot movable ring 10 to such an angle that the brushes B_{2A}, B_{2B}, B_{2C} jump from contacts d to contacts f .

It is therefore possible in this manner to have brushes B_1 and B_2 move on all contacts in one direction or the other according to the direction of rotation applied by pinions 8 and 11 through the Maltese cross arrangement.

In the case of a regulating system by inversion or remote control, it is known that the three brushes B_1 and the three brushes B_2 after having gone through the regulating range a first time by successively moving, on the one hand, on contacts c to o and, on the other hand, on contacts b to n start the same cycle again after selecting switch 1 has either reversed the direction of the regulating winding or transferred the reserve winding (position 3 and position 1 of selecting switch 1 shown in FIG. 1).

Because, in the instant invention, the contacts of one phase are consecutive and in the same numerical order as the contacts of the two other phases, the maximum voltage between the last contact of one phase and the first contact of the following phase is at the most equal to the total regulating winding phase voltage. Owing to

this arrangement, the spacing between two adjacent contacts belonging to two different phases can be the same as that of two consecutive contacts of one phase. It is therefore only necessary, in order to cover the regulating range a second time, to continue the movement in the same direction. The brushes B_1 can move from contacts o of one phase to contacts c of the following phase; the same being true of the brushes B_2 which can move from contacts n to contacts b since segments S_{1A}, S_{1B}, S_{1C} as well as segments S_{2A}, S_{2B}, S_{2C} are insulated from one another.

An embodiment of such a selector is diagrammatically illustrated in FIGS. 3 and 5. It is made up of an insulating cylinder 5 on which are secured, at the periphery of one of its ends, the odd-numbered fixed contacts P_1 and at the other the even-numbered fixed contacts pp of the three phases as shown in FIGS. 2 and 3. Each of these contacts has the form of a U, one leg of which lies outside and is parallel to the generating lines of cylinder 5 and the other leg is inwardly of the cylinder and form connecting lugs 13.

In their outer portion, the contacts of each phase are successively placed in communication by means of brushes B_1 or B_2 with segments S_1 or S_2 associated therewith. Brushes B_1 are secured at their center to ring 6 and brushes B_2 to ring 10.

Each of the said rings rotate on two circular rolling paths 14 and 14' through the medium of rollers 15 and 15' arranged in groups of 2. The groups are secured onto the rings and spaced 120° from one another.

The rollers are elastically mounted on the rings in order to overcome the small imperfections caused by their assembly on a large diameter cylinder.

Rings 6 and 10 are driven step-by-step in one direction or the other by means of a known mechanism, such as the Maltese cross type drive CM.

A driving plate 19 receives its motion from an electric control box, not shown, by means of an insulating shaft 16 and two conical pinions 17 and 18. By means of a pin 20, driving plate 19, which makes a half turn for each position, successively hooks onto Maltese cross 21, integral with pinion 8, and Maltese cross 22, integral with pinion 11, in one direction or the other according to the direction of rotation of shaft 16.

This will permit, through the medium of racks 7 and 12, to rotate movable rings 6 and 10 and to thus change the position of brushes B_1 and B_2 .

The assembly is supported by a horizontal insulator 23 provided with a transverse plate 24 guiding the conductors ap which join the regulating taps to the connection lugs 13.

The selector is protected by means of an anti-brush discharge hood 27.

It is obvious that modifications can be made to the above described apparatus without departing from the spirit of the instant invention, the scope of which is defined in the appended claims.

The embodiments of the invention in which an exclusive property or privilege is claimed are defined as follows:

A tap selector for switches used in the voltage regulation of loaded three-phase transformers having regulating taps distributed on the upper portion of the transformer windings, said selector comprising: an insulating cylinder; evenly spaced tap contacts divided into two groups, one group located at one end of said cylinder and comprising the odd-numbered tap contacts of each phase of the transformer and one second group located at the other end of the cylinder and comprising the even-numbered tap contacts of each phase of the transformer; the effective surface of each said tap contacts being located outside said cylinder and the connecting lug of said tap contacts being located inside said cylinder; a rotatable annular ring surrounding said cylinder near each group of tap contacts; supporting means for said rings disposed

to roll on the outer surface of said cylinder; means for rotating said rings each after the other by successive angular displacements corresponding to the spacing of the adjacent tap contacts; three arcuate conducting segments secured on said cylinder opposite the tap contacts with respect to each ring; said segments encircling substantially a third of the circumference of said cylinder but being electrically insulated from each other by sufficient gaps; a brush corresponding to each segment, fixed to said ring; said brushes being spaced 120° from each other and adapted to successively join the tap contacts to the segments.
